UNITED STATES PATENT OFFICE.

ZEMACH AUERBACH, OF NEW YORK, N. Y.

APPOINTMENT FILE OR RACK.

1,414,721.

Specification of Letters Patent. Patented May 2, 1922.

Application filed December 21, 1921. Serial No. 523,844.

To all whom it may concern:

Be it known that I, ZEMACH AUERBACH, a citizen of Russia, and resident of New York city, borough of Manhattan, in the 5 county of New York and State of New York, have invented certain new and useful Improvements in Appointment Files or Racks, of which the following is a specification.

10 An object of my invention is to provide a simple, inexpensive and effective rack or holder for cards and folders adapted to detachably retain the cards or folders, the device being particularly adapted for keeping 15 records for appointments, data of various kinds, and for retaining letters and the like.

Another object is to provide a card or holder adapted to be supported in the rack, and having the characteristic of providing 20 for a relatively large space for making memoranda thereon in a small compass, the card or folder being also adapted to contain letters and other documents.

Reference is to be had to the accompanying drawings forming part hereof, wherein—

Figure 1 is a front view of my improved rack or holder;

Fig. 2 is an enlarged vertical section on 30 line 2, 2, in Fig. 1;

Fig. 3 is a cross section on line 3, 3, in Fig. 1;

Fig. 4 is an edge view of a single ply card;

35 Figs. 5 and 6 are edge views of folded cards or holders;

Figs. 7 and 8 are respectively perspective views of the cards of Figs. 5 and 6;

Fig. 9 is a diagrammatic view illustrating 40 the manner of forming the card retainers of the rack;

Fig. 10 is a broken perspective view of the rack in the form of a compartment, and

Fig. 11 is a side view of Fig. 10, partly in 45 section.

Similar numerals indicate corresponding parts in the several views:

The rack mainly comprises a body 1 around which is wound a strip 2 in a manner to partly overlap itself, and marginal binding 3. In the form shown in Figs. 1, 2, 3 and 9 the body 1 is illustrated as a flat relatively thin sheet or board, say of pasteboard, around which the strip 2 is wound, 55 in an endless manner, as in a diagonal direction, so that the adjacent runs or layers

of the strip will partly overlap one another, providing passage-ways or slots 4 at the upper edges 2^a of the respective runs or layers of the strip to admit therebetween 60 the cards 5. The strip may be of suitable fabric, such as tape, although the strip may be of suitable paper, metal or other material. Along the margins of the body, over the layers of the strip at the edges of the 65 body, the bindings 3 are fastened to retain the strip layers in place and to cooperate with the cards. The binding may be of paper or cloth, preferably folded in U-form to embrace the margins of the wound body, 70 as shown in Fig. 3, the bindings being secured to the strip and the body by suitable adhesive. As shown in Fig. 1 the end portions of adjacent bindings overlap one another, the bindings extending completely 75 around the body and serving as a finish for its edges and to confine the strip in its proper wound condition on the body.

The cards 5 are shown provided with lateral projections 5^a at their upper edges to 80 cooperate with the adjacent binding strip to retain the card in place between two overlapping portions of strip 2. The construction described provides overlapping runs or layers of strip 2 on opposite sides 85 of body 1 to receive cards on each side of the latter, (Figs. 2 and 3).

The device may have one or more vertical rows of the overlapping runs or layers of strip 2. In Fig. 1 two such vertical rows 90 are provided by means of a binding strip 6, spaced between the vertical marginal strips 3, the adjacent projections 5^a of cards 5 cooperating with strip 6, the edges 2^a of wound strip 2 being between bindings 3 at 95 the sides and the intermediate binding strip 6. Strip 6 is preferably glued to the strip 2 as well as to the end bindings 3. When it is desired that the rack shall indicate time for appointments the binding strip 6 is provided with opening 6^a, in register with corresponding runs of strip 2, the mid-portion of strip 6 having the openings 6^a being loose from strip 2 and from bindings 3, the margins of strip 6 adhering thereto, providing 100 a space 7 in which an elongated time card 8 is adapted to be slid, said card 8 being provided with numerals at 9 to appear through openings 6^a. In like manner one of the marginal bindings 3 may have openings 3^a, registering laterally with openings 6^a, said strip 3 having its mid-portion loose to admit 110

a time card 8. A card 5, having the name of a caller exposed along its top portion, may be inserted in the appropriate part of the rack to hang alongside of the appointed 5 time on card 8. The cards 8 may be replaced to vary the succession of the units of time thereon according to requirements.

While the cards 5 may be of a single thickness of material, (Fig. 4), adapted to 10 have memoranda written or printed thereon, the cards also may be folded, whereby to extend their length from the normal condition as shown in Figs. 7 and 8. In the examples shown, the cards may be in the form of 15 strips of paper of suitable length folded at 5^b to form double ply of thicknesses provided with lateral projections 5^c, at the opposite free ends of which cards are the projections 5^a, and such folded cards may be again 20 folded substantially midway at 5^d to reduce the length of the cards and provide extended surfaces on both sides thereof, to be written or printed upon. The folded cards may be inserted in the rack in the 25 manner before described to hang therein by their projections 5^a, 5^c.

While the name or the designation may be written or printed upon the upper edge portion of card 5, as shown in Figs. 1 and 7, 30 the upper edge portion may be folded over as indicated at 10, (Fig. 8), the lower edge thereof being stuck to the card for a distance to provide a pocket or guideway to receive a detachable card 11, having a name 35 or designation thereon that will appear through an opening 10^a in the folded over portion 10, so that such cards 11 may be inserted and replaced as may be required.

Instead of providing the rack with a body 40 1 comprising a single thickness of material around which the strip 2 is wound, said body may be in frame-like form to provide a compartment, as indicated at 1^a in Figs. 10 and 11. The strip 2 will be wound in 45 overlapping form around the box body 1^a, in manner before described with respect to flat body 1, to provide the spaces or guideways 4 for the cards, and the binding 3 will be secured around the edges of the box body 50 over the adjacent windings. The wound strips 2 are thus located at the open front of the box body providing a compartment or chamber 12 within the body behind the front strips 2 wherein the cards or holders 5 may be contained to be supported in the 55 manner before described.

An advantage of said compartment-like body construction is, that the cards or folders 5 may be used to contain letters and 60 other documents for filing, whereby, for instance, a number of letters and the like, pertaining to a person, firm, or corporation,

may be filed in one of the folders 5 with the name of such party appearing thereon in front of the rack to enable ready access to 65 letters, bills, etc., of such party.

My improvements may be made in an inexpensive manner and are adapted to detachably retain the cards or folders for convenient use and reference, in the manner before set forth, either in conjunction with numerals indicating units of time or without the same.

The term "card" is used with respect to the parts 5 whether in a single piece or folded one or more times, and provided with means to support them upon the rack.

Having now described my invention, what I claim is:

1. A rack of the class described comprising a body and a strip wound in overlapping relation providing passage-ways therebetween for cards, and bindings at opposite sides of the body secured over the adjacent portions of the strip. 80

2. A rack of the class described comprising a body and a strip wound in overlapping relation providing passage-ways therebetween for cards, and bindings at opposite sides of the body secured over the adjacent portions of the strip, one or more of said bindings having a mid-portion providing a space unsecured to the strip and provided with openings registering with the runs of the strip, and a card having time indications 90 thereon adapted to be inserted in the space behind the binding to show its time indications 95 through said openings.

3. A rack of the class described comprising a body having a strip wound around the same in a diagonal direction, the runs of the strip overlapping one another providing passage-ways therebetween, and bindings secured upon the strip at opposite edges of the body to retain the runs of the strip in 100 place on the body. 105

4. A rack of the class described comprising a hollow body open on one side and provided with a strip wound around the same 110 providing overlapping layers having passage-ways therebetween to admit cards, and means at the edges of the body to retain the strip layers in place.

5. A rack of the class described comprising a hollow body open on one side and provided with a strip wound around the same 115 providing overlapping layers having passage-ways therebetween to admit cards, and bindings at the edges of the body secured over the adjacent layers of the strips. 120

Signed at New York city, in the county of New York, and State of New York, this 19th day of December, A. D. 1921.

ZEMACH AUERBACH.
